Samuel Meyerson, West Hempstead, N. Y.

Application February 9, 1956, Serial No. 40,089

Term of patent 3½ years

(Cl. D45—4)

FIG. 1.

FIG. 2.

FIG. 3.

FIG. 4.

FIG. 5.

FIG. 6.

FIG. 7.

Figure 1 is a top plan view of an expandable link chain for a bracelet or the like embodying my new design;

Figure 2 is a side elevation thereof with the conventional bottom links illustrated in broken lines;

Figure 3 is a top plan view showing the chain in an expanded position;

Figure 4 is an enlarged perspective view of the shell of one of the ribbed form of top links;

Figure 5 is a longitudinal section of the shell of the link shown in Fig. 4, line 5—5;

Figure 6 is a perspective view of the shell of one of the links spacing the ribbed links; and

Figure 7 is a longitudinal section of the shell of this link shown in Fig. 6 on line 7—7.

The dominant feature of the design resides in the elements shown in full lines.

I claim:

The ornamental design for an expandable link chain for a bracelet or the like, as shown and described.
